O. SCHWEISGUT

EARTH AUGER

Filed July 15, 1921

Inventor:
Otto Schweisgut
by *Paul Schilling*
his attorney.

UNITED STATES PATENT OFFICE.

OTTO SCHWEISGUT, OF MUNICH, GERMANY, ASSIGNOR OF ONE-HALF TO FRIEDRICH WAHRENBURG, OF MUNICH, GERMANY.

EARTH AUGER.

Application filed July 15, 1921. Serial No. 484,944.

To all whom it may concern:

Be it known that I, OTTO SCHWEISGUT, a citizen of the German Republic, and a resident of Munich, Germany, have invented a certain new and useful Improved Earth Auger (for which I have filed application in Germany April 12, 1920), of which the following is a specification.

This invention relates to an earth auger, 10 the configuration of which is such that the earth which the spirally shaped auger blade has loosened may be easily, and without loss, removed from the bore hole. This is attained by making a flap which is hinged 15 to the blade, preferably at its upper end, longer than the height of the blade passage and connecting it with the blade or blade-end by an eye or the like, in such a manner, that it may freely swing upwardly 20 and downwardly, as is more fully described hereinafter.

In order to make my invention more clear, I refer to the accompanying drawing which shows by way of example a perspective illustration of the working end of an earth auger constructed according to this invention.

The auger consists in general in known manner of a body or shaft *b* having at its 30 upper end a handle and at its lower end a worm *a* of suitable diameter and rather steep pitch. The lowermost end of the body or shaft *b* is provided with a pointed foot *c*.

To the upper end of the worm *a* is hinged 35 the flap *d* which, although known per se, is, in the case in question, bent and curved correspondingly to the worm. Preferably the flap is attached to the worm by an eye *e*, in such a manner, that it may swing upwardly and downwardly in any direction. The length of the flap depends upon the

height of the worm passage and is a little greater than this latter.

During the boring operation the flap is in the position shown in dotted lines and 45 forms thus a continuation of the worm; it does not impede the boring operation in any way. If, finally, the auger is to be drawn out of the bore hole, it is prior thereto turned a little in the opposite direction whereby the flap is depressed into the position shown in full lines, in which its free end contacts with the worm portion below it; in this position of the flap it closes the space between said worm portion and the upper worm end, whereby the earth present above the worm is prevented from gliding down upon the sloping worm blade. The earth is lifted together with the auger, 50 without any remainder, and neither particular precaution is, nor special means are, necessary to that effect.

Having now described my invention, what I claim as new and desire to secure by Letters Patent of the United States is:

1. An earth auger of the character set forth, comprising in combination with a shank and a steep-pitched cutting worm, a flap curved in continuation of the curvature of said worm, and a universal hinge 70 connection between said worm and said flap.

2. An earth auger of the character set forth, comprising in combination with a shank, a steep-pitched cutting worm, a flap 75 closely conforming to the curvature of said worm and somewhat longer than the height of the worm pitch, and a single ring hinge-connection between said worm and said flap.

In testimony whereof I affix my signature.
OTTO SCHWEISGUT.
